[57] CLAIM

The ornamental design for a glass reflector for dual headlight assembly, as shown and described.

DESCRIPTION

FIG. 1 is a front elevational view of a glass reflector for a dual headlight assembly showing my new design; FIG. 2 is a top plan view, the bottom plan view being identical;

FIG. 3 is a side elevational view as viewed along line 3—3 of FIG. 2 and rotated 90°;

FIG. 4 is a side elevational view as viewed along line 4—4 of FIG. 2 and rotated 90°; and

FIG. 5 is a rear elevational view as viewed along line 5—5 of FIG. 2.
